UNITED STATES PATENT OFFICE

NAT P. STECKLER, OF NEW YORK, N. Y.

DESIGN FOR A NURSING BOTTLE NIPPLE WITH CORRUGATED HANDLES

Application filed April 3, 1933. Serial No. 47,678. Term of patent 14 years.

To all whom it may concern:

Be it known that I, NAT P. STECKLER, a citizen of the United States, residing at 106 East 19th Street, New York, in the county of New York and State of New York, have invented a new, original, and ornamental design for a Nursing Bottle Nipple with Corrugated Handles, of which the following is a specification, reference being had to the accompanying drawing, forming part thereof.

Fig. 1 is a top plan view of a nursing bottle nipple with corrugated handles.

Fig. 2 is a front elevation thereof showing my new design.

I claim:

The ornamental design for a nursing bottle nipple with corrugated handles, as shown.

NAT P. STECKLER.
